UNITED STATES PATENT OFFICE.

THOMAS F. PRYOR, JR., OF SOUTH ORANGE, NEW JERSEY, ASSIGNEE TO B. M. SHANLEY, JR. CO., A CORPORATION OF NEW JERSEY.

BELT CLASP OR BUCKLE.

1,133,666.

Specification of Letters Patent. Patented Mar. 30, 1915.

Application filed February 18, 1914. Serial No. 818,592

To all whom it may concern:

Be it known that I, THOMAS F. PRYOR, Jr., a citizen of the United States, residing at South Orange, in the county of Essex and 5 State of New Jersey, have invented certain new and useful Improvements in Belt Clasps or Buckles; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification.

This invention has reference, generally, to improvements in clasps or holding devices; and, the present invention relates, more particularly, to a novel clamping 20 means or holding device, in the form of a buckle which is especially adapted for use in connection with the respective end-portions of belts, such as are worn with garments.

The invention has for its principal object 25 to provide a novel and simply-constructed clasp or fastening for belts and other uses, which is readily attached to the belt or strap, and the clamping member of which, when in engagement with the free end-portion 30 of the belt, firmly and positively clamps or grasps the said end-portion of the belt, so that no matter how great the pull or strain, the clasp or fastener will not become displaced, but can be readily removed 35 or adjusted by the application of a slight lifting pressure upon the back of the main body of the buckle, so as to thereby provide a sufficient disengagement of the clamping member with the belt-portion, so as to permit 40 it the latter to be slid back and forth upon the back of the buckle for proper adjustment, or for the removal of the belt from the body of the wearer.

Other objects of the present invention will 45 be clearly understood from the following detailed description of the present invention.

The invention is clearly illustrated in the accompanying drawings, in which:—

50 Figure 1 is a plan view of a belt-clasp or

fastener made according to the principles of the present invention, said view showing in connection therewith, and in plan, the two end-portions of a belt with which the clasp or fastener is employed; and Fig. 2 55 is a side elevation of the belt-clasp or fastener and the belt-portions, represented in said Fig. 1. Fig. 3 is a longitudinal vertical section of the belt-clasp and the two end-portions of the belt, one end of the belt 60 being attached to a loop-portion of a clamping member pivotally connected with the back of the main body of the clasp, and the other end-portion of the belt being represented in its clamped relation with the said 65 clamping member. Fig. 4 is a similar sectional representation of the various parts shown in said Fig. 3, but illustrating the pivoted clamping member in its disengaged relation with the free end-portion of the 70 belt. Fig. 5 is a rear face view of the belt-clasp or buckle in its detached relation from the belt or strap.

Similar characters of reference are employed in the above described views, to indicate corresponding parts.

Referring now to the several figures of the drawings, the reference-character 1 indicates a complete belt-clasp or buckle showing one embodiment of the principles of the 80 present invention, and the same comprises a suitably formed and suitably ornamented face-plate, as 2, which is preferably outwardly convexed, substantially as shown in Figs. 2, 3 and 4 of the drawings. The said 85 face-plate is formed upon its rear face and at its longitudinally extending marginal edge-portions with rearwardly extending marginal rib-like flanges, as 3, the respective flanges 3 being connected at or near their 90 respective end-portions by means of laterally extending plates or bar-like members 4 and 5, one of said members, as 5, being provided with rearwardly extending pintle-receiving ears or lugs, as 6. Within the 95 said perforated ears or lugs 6 is secured a pintle 7, and pivotally mounted upon said pintle are the perforated ears or lugs 9 of a loop-shaped clamping member 8. At a point between the said ears or lugs 9 and 100

the part 10 of said member 8, and to project inwardly in a direction toward the back of the face-plate 2, is a clamping jaw 11 which is formed with a suitably shaped 5 grasping edge, preferably chamfered, as at 12, so as to be adapted to be brought into biting and retaining engagement with the free end-portion of the belt in the manner and for the purposes to be presently described.

In applying the belt-clasp or buckle to the belt, the one end-portion 13 of the belt is inserted in the opening of the loop-shaped member 8 and securely fastened about the 15 portion 14 of said member 8. The free end-portion 15 of the belt is then passed over the laterally extending plates or bar-like members 4 and 5, so that said portion of the belt will lie directly against the rear face 20 of the face-plate 2, substantially as illustrated in Fig. 4 of the drawings. The free slidable arrangement of the belt-portion 15 upon the back of the buckle, and between the guiding flanges 3 and above the said 25 plates or bar-like members 4 and 5 allows for a quick and easy adjustment of the belt and buckle about the body of the wearer. After proper adjustment, the loop-shaped member 8 automatically moves in the direction of the arrow α , thereby moving the clamping jaw 11 into its biting and clamped retaining engagement with the end-portion 15 of the belt, as clearly represented in Fig. 3 of the drawings.

35 It will be fully evident from an inspection of said Fig. 3 that no matter how great a pull is exerted in the direction of the arrow γ upon the end-portion 15 of the belt, the more securely will the belt-portion be 40 clamped between the rear of the face-plate 2 and the clamping edge 12 of the clamping jaw 11, as will be clearly understood from an inspection of said Fig. 3 of the drawings.

To re-adjust the belt upon the body of 45 the wearer, or to remove the belt, all that is necessary is for the operator to place the thumb back of the face-plate of the buckle and press slightly in an outward or forward direction, whereby the clamping engagement 50 of the jaw 11 with the belt-portion 15 becomes broken, so that the buckle may be adjusted with relation to the free end-portion of the belt, or that portion of the belt may be entirely removed from the buckle.

55 From the foregoing description of the present invention it will be clearly seen that I have devised a simply constructed belt-clasp or buckle which can be cheaply made, is readily adjusted with relation to the belt, 60 and the grasping and pulling action of which is most positive, no matter how great the pull or strain, so that the belt will be properly retained in its secured relation about the body of the wearer.

I claim:—

1. In a belt-buckle, a main body comprising a convexly formed face-plate and longitudinally extending guide-flanges projecting from the rear face of said face-plate, at the marginal edge-portions thereof, bar-like 70 members connected with the respective end-portions of said guide-flanges, said bar-like members extending laterally across the rear face of said face-plate and forming with the respective end-portions of the face-plate 75 strap-receiving and guiding spaces, pintle-receiving ears connected with one of the laterally extending marginal edges of one of said bar-like members, combined with a loop-shaped member to which an end of a 80 belt-strap is adapted to be attached, pintle-receiving ears extending from said loop-shaped member into registration with the pintle-receiving ears of said bar-like member, a pintle extending through the said registering ears, all arranged so that the said loop-shaped member is pivotally connected 85 with relation to the said face-plate at one laterally extending edge-portion thereof and is adapted to be projected longitudinally 90 beyond the said edge-portion of the face-plate in the clamping position, and a clamping means connected with the said loop-shaped member and adapted to be moved against a belt-portion arranged back of the 95 said face-plate for pinching the belt-portion against the laterally extending marginal edge-portion of the face-plate, substantially as and for the purposes set forth.

2. In a belt-buckle, a main body comprising 100 a convexly formed face-plate and longitudinally extending guide-flanges projecting from the rear face of said face-plate, at the marginal edge-portions thereof, bar-like 105 members connected with the respective end- 110 portions of said guide-flanges, said bar-like members extending laterally across the rear face of said face-plate and forming with the respective end-portions of the face-plate strap-receiving and guiding spaces, pintle- 115 receiving ears connected with one of the laterally extending marginal edges of one of said bar-like members, combined with a loop-shaped member to which an end of a belt-strap is adapted to be attached, pintle- 120 receiving ears extending from said loop-shaped member into registration with the pintle-receiving ears of said bar-like member, a pintle extending through the said registering ears, all arranged so that the said loop-shaped member is pivotally connected 125 with relation to the said face-plate at one laterally extending edge-portion thereof and is adapted to be projected longitudinally beyond the said edge-portion of the face-plate in the clamping position, and a clamping jaw extending angularly from the hinged portion of the said loop-shaped

member and laterally across the rear face of the face-plate, said jaw being adapted to be moved against a belt-portion arranged back of the said face-plate for pinching the belt-portion against the laterally extending marginal edge-portion of the face-plate, substantially as and for the purposes set forth.

In testimony, that I claim the invention set forth above I have hereunto set my hand this 12th day of February, 1914.

THOMAS F. PRYOR, JR.
